S. A. BOHRER

REVERSIBLE CUFF

Filed Jan. 24, 1921

Patented Feb. 13, 1923.

1,444,901

UNITED STATES PATENT OFFICE.

STUART A. BOHRER, OF CHICAGO, ILLINOIS.

REVERSIBLE CUFF.

Application filed January 24, 1921. Serial No. 439,575.

To all whom it may concern:

Be it known that I, STUART A. BOHRER, a citizen of the United States, residing at Chicago, in the county of Cook and State of Illinois, have invented certain new and useful Improvements in Reversible Cuffs, of which the following is a description.

My invention relates to improvements in reversible cuffs, and more specifically to a reversible cuff for a garment sleeve, which will have all the outward appearances of being an ordinary soft cuff and yet will give double the wear of an ordinary soft cuff, before it is necessary to have it laundered. The invention has among its objects the production of a cuff of the kind described, which is simple, convenient, durable and attractive, efficient and satisfactory.

Another object of my invention is to form such a cuff so that it will be properly reinforced and be extremely durable. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is an elevation of my improved cuff with a portion broken away;

Fig. 2 is an elevation of the same with the cuff reversed and showing parts diagrammatically in section;

Fig. 3 is a section taken substantially on line 3—3 of Fig. 1; and

Fig. 4 is a section taken substantially on line 4—4 of Fig. 2.

In the embodiment of my invention illustrated in the drawings, 1 represents the lower portion of a garment sleeve, for example a shirt sleeve, having a bottom edge 2. Secured to the bottom of the sleeve, adjacent the edge 2, is my improved reversible cuff 3, the same being preferably made of a single sheet of material of the desired size and shape, folded centrally upon itself as indicated at 4, this folded edge forming the bottom or extreme edge of the cuff when in its extended position. The top and side meeting edges of the said folded sheet are preferably folded inwardly and secured to-

gether by stitching 5 and 5' respectively, or by any other suitable or equivalent means, said stitching being preferably extended entirely along the cuff edges and including the extreme folded over portion at edge 4, as indicated at 6. The stitching gives more body to the material, strengthening it and thereby improving its wearing qualities.

The cuff 3 is secured to the sleeve in any suitable manner, as shown to the exterior of the sleeve by a row of stitching 7, said row of stitching, however, being spaced downwardly or backwardly of the free edge of said cuff so that when the cuff is reversed as shown in Fig. 4, it will provide a finished edge simulating the edge of the ordinary soft cuff, and also edge 4, as indicated in Fig. 3. The cuff 3 comprises two main portions, namely the upper section 8, which is secured to the shirt sleeve and the lower section 9, said portions being adapted to be folded on the line parallel to the bottom edge 4, as indicated at 12, and superimposed one upon the other so that the lower portion will cover the upper portion, and thus keep the same clean until the cuff is ready to be turned or reversed.

It may be mentioned that I prefer to only stitch one portion of the material in the upper section 8 to the sleeve portion, as indicated at 7' in Figs. 3 and 4, so that the stitching does not show through when the lower portion is turned inwardly, as will be further described. A strip of tape 10 or other suitable reinforcing and stiffening material may be, and is preferably, arranged on the inner side of the sleeve along the line of securing of the cuff and sleeve at the extreme edge 2 of the sleeve portion 1, which prevents the sleeve edge from raveling and reinforces the same.

It will be noted that the side edges or ends of the cuff portions preferably project beyond the edge of the sleeve portion, as indicated at 13 in Figs. 1 and 2.

When it is desired to reverse the cuff, the lower portion 9 is turned about its line of fold at 12 and inwardly as indicated in Fig. 4, thereby exposing the upper part 8, and allowing the finished edge 7 to show, giving the appearance of an ordinary soft cuff edge. The side edges may be secured together in any desired manner, as for example by the usual cuff buttons (not shown), and I have shown button holes 11 representing suitable fastening means for cooperat-

ing with the buttons, the button holes being provided at the outer sides or edges of both the top and bottom cuff portions. These button holes may be arranged as desired, 5 preferably so that they come into registry when the lower portion is superimposed on the outer side of the upper portion, as illustrated in the drawings, and it may be mentioned, that if desired these holes may be so 10 arranged that the free edge of the lower portion projects slightly beyond the edge 7 of the portion 8, as shown in Fig. 3, so that the edge 7 is kept clean until the cuff is ready to be turned. This is a matter of preference, 15 however, and I have shown the edge 4 projecting a considerable portion beyond the edge 7 in order to clearly bring out this point. In actual practice, the edge portion will generally not project as much as indicated, as it is only necessary to bring it to 20 a point where it will substantially protect the inner edge. When the cuff is reversed as shown in Fig. 4, it will be noted that the edge portion 7 is substantially free of the 25 sleeve portion 1 so that the same clearly appears as a separable cuff, rather than as a sewed on or turned-over cuff.

Having thus described my invention, it is obvious that various modifications may be 30 made in the same without departing from the spirit of my invention; hence I do not wish to be understood as limiting myself to the exact form, construction, arrangement and combination of parts herein shown and 35 described, or uses mentioned.

What I claim as new and desire to secure by Letters Patent is:

1. In combination with a garment sleeve, 40 a reversible cuff comprising a single sheet of material folded centrally upon itself to form a two-ply part, the free edges being brought together and stitched through both of said edges and secured only to the exterior of the sleeve along a line spaced rearwardly of 45 said free edges, said two-ply part being adapted to be folded over either inwardly or outwardly of said sleeve along a line parallel to said central fold to form a cuff part attached at one edge to said sleeve and 50 a fold-over cuff part.

2. In combination with a garment sleeve, 55 a reversible cuff comprising a single sheet of material folded upon itself centrally to form a two-ply part, the free edges of said material being inturned and being brought together into registry and stitched thereat through both edges and secured only to the

exterior of the sleeve along a line spaced rearwardly of said free edges, said two-ply part being adapted to be folded over either 60 inwardly or outwardly of said sleeve along a line parallel to said central fold to form a cuff part attached at one edge to said sleeve and a fold-over cuff part, and a pair of buttonholes at each side edge of said cuff, one 65 of each of said pairs of buttonholes being in the fold-over part of the cuff and the other in the attached part, the buttonholes in said fold-over part being at a greater distance 70 from the free edge of said part than are the buttonholes in the attached part from the attached edge thereof, all of said buttonholes adapted to register and receive a single button, whereby the free edge of the 75 fold-over part covers and projects beyond the attached part in either of its reversed positions.

3. In combination with a garment sleeve, 80 a reversible cuff comprising a single sheet of material folded centrally upon itself to form a two-ply part, the free edges of said material being inturned and being brought together into registry and stitched thereat through both of said edges and secured only to the exterior of the sleeve along a line spaced rearwardly of said free edges, 85 said two-ply part being adapted to fold over either inwardly or outwardly of said sleeve along a line parallel to said central fold to form a cuff part attached at one edge to said sleeve and a fold-over cuff part, and a pair of buttonholes at each side of said cuff, one 90 of each of said pairs of buttonholes being in the fold-over part of the cuff and the other in the attached part, the buttonholes in said fold-over part being at a greater distance 95 from the free edge of said part than are the buttonholes in the attached part from the attached edge thereof, all of said buttonholes adapted to register and receive a single button, whereby the free edge of the fold-over part covers and projects beyond the attached part in either of its reversed 100 positions, and a reinforcing strip secured to the bottom of said sleeve at its juncture with 105 said cuff.

In testimony whereof, I have hereunto signed my name in the presence of two subscribing witnesses.

STUART A. BOHRER.
